UNITED STATES PATENT OFFICE.

WILLIAM H. S. MOORE, OF WEST CHICAGO, ILLINOIS.

MAGAZINE-HANDLE.

1,105,818.

Specification of Letters Patent.

Patented Aug. 4, 1914.

Application filed June 16, 1913. Serial No. 773,819.

To all whom it may concern:

Be it known that I, WILLIAM H. S. MOORE, a citizen of the United States, residing in West Chicago, in the county of DuPage and 5 State of Illinois, have invented a new and useful Improvement in Magazine-Handles, of which the following is a specification.

This invention relates to an improvement in combined tools and especially to combining together a carpenter's hammer and a nail-set intended for use therewith, and the 10 invention consists in the novel devices and combinations of parts and devices herein-after more fully set forth and made the subject matter of claim.

In the accompanying drawing, which forms a part of this specification, Figure 1 is a side view of a hammer and nail-set combined in the manner of my invention. Fig. 2, on a larger scale, is a section of the same on the line 2-2 of Fig. 1. Fig. 3 is a section on the line 3-3 of Fig. 2. Fig. 4 is a section on the line 4-4 of Fig. 2. Fig. 5 is a side view of the tilting nail-set sheath or carrier.

The prime object of the present improvement is to combine with the handle of the hammer a spring-held tilting sheath, socket or carrier to receive the nail-set in such a 30 fashion and manner that the tilting sheath or carrier may be manipulated with one finger of the hand carrying the hammer to throw the sheath out into a position where the nail-set can be readily seized and removed by the fingers of the other hand when 35 it is desired to use the nail-set in conjunction with the hammer, and to as readily replace the same into the socket.

In the said drawings A represents the 40 hammer.

B is the usual wooden hammer handle which is mortised or cut to receive the tilting nail-set sheath now to be described. This mortise or cavity C is placed in the side of 45 the hammer handle. And if the hammer is to be used by a right-handed person the cavity is cut in the left-hand side of said handle as illustrated in the drawing. In this cavity is fitted the frame D which may be secured 50 to the handle by the two small screws d. Mounted in this frame is the tilting nail-set carrier E pivoted on the pivot e. Within 55 the cavity is the spring F which may be secured to the stud f on the carrier and which bears against one end of the tilting sheath E tending to hold the said tilting sheath in the

closed or retracted position. To swing the sheath open a finger of the operator's right hand,—say the second or third finger, which lies immediately over the part or finger-hold G of the tilting sheath,—is pressed inward, throwing the short end of the tilting sheath in against the spring and the long end of said sheath out, as indicated in dotted lines at Fig. 2, thus opening the 60 sheath and bringing the nail-set H into position so that the end of the same may be seized by the fingers of the other hand, after which the pressure of the finger on the tilting sheath being released said sheath flies 65 back and the hammer is in perfect condition to be used with the set. To replace the set the tilting sheath is again pressed out, the set inserted in the sheath and the sheath permitted to spring back into closed position. 70 The whole arrangement is such that the nail-set when not in use is carried safely and without any inconvenience in the hammer handle and also such that when required, the hammer being in the right hand it is only 75 necessary to compress a finger of that hand and bring the other hand into position to receive the nail-set for use or return it to place after use. A little practice enables this to be done by the workman without 80 looking and a great convenience in manipulation is thus secured along with the fact that the nail-set is always present with the handle when required. It will also be noted that the whole sheath device may be set in 85 and secured to the handle grip by merely recessing the grip and putting in the screws that hold the device in place therein; and the device is then flush with the handle surface.

My invention is hereinabove set forth as embodied in a particular and preferable form of construction, but may also be embodied in other forms of construction within the claims hereinafter made.

I claim:

1. The combination with a tool handle grip, of a tilting, spring-held nail-set sheath adapted to receive a nail-set mounted on said grip and adapted to be operated by the 105 fingers of the user's hand when the latter is in its normal position while holding the grip, substantially as specified.
2. The combination with a hammer handle, of a nail-set sheath pivoted intermediate 110 its ends in the side of the hammer handle and having one of its ends held in and the

other held out by means of a spring, the held out end being opposite the fingers of a hand holding the hammer handle.

3. The combination with a tool handle-grip, of a movable, disappearing tool-sheath, having a tension device to retain it in normal position, and adapted to receive a supplementary tool, the outer surface of said tool sheath lying flush with the surface of the handle-grip when in normal position, substantially as specified.

4. The combination with a tool handle-grip, of a tool-sheath for a supplementary tool, the sheath being rockably mounted on

a pivot located intermediate its ends and disappearing in the side of the grip and having one end held in and the other held out by means of a tension device, the held out end being opposite the fingers of a hand holding the grip.

In testimony whereof I have hereunto set my hand in the presence of two subscribing witnesses.

WILLIAM H. S. MOORE.
